Primary Examiner — T. Chase Nelson*Assistant Examiner* — Mark Cavanna(74) *Attorney, Agent, or Firm* — Whyte Hirschboeck Dudek S.C.; James A. Joyce**CLAIM**

An ornamental design for a table top implant tracking device with a transparent sheath, as shown and described.

DESCRIPTION

FIG. 1 is a perspective view of a table top implant tracking device with a transparent sheath showing my new design;
 FIG. 2 is a front elevation view thereof;
 FIG. 3 is a top plan view thereof;
 FIG. 4 is a right elevation view thereof;
 FIG. 5 is a left elevation view thereof; and,
 FIG. 6 is a bottom plan view thereof.
 The broken lines are included for the purpose of illustrating portions of the table top implant tracking device that form no part of the claimed design.
